UNITED STATES PATENT OFFICE.

HERMAN TRZECIAK, OF WAKPALA, SOUTH DAKOTA.

NEEDLE-THREADING DEVICE.

Application filed November 28, 1923. Serial No. 677,418.

To all whom it may concern:

Be it known that I, HERMAN TRZECIAK, a citizen of Poland, residing at Wakpala, in the county of Corson and State of South Dakota, have invented certain new and useful Improvements in Needle-Threading Devices, of which the following is a specification.

This invention relates to new and useful improvements in needle threading devices.

An important object of the invention is to provide a device which will successfully thread hand or sewing machine needles.

A further object of the invention is to provide a device of the above mentioned type which is of exceedingly simple construction and one that may be manufactured at a very nominal cost.

Other objects and advantages of the invention will be apparent during the course of the following description.

In the accompanying drawing forming a part of this specification and in which like numerals are employed to designate like parts throughout the same,

Figure 1 is a side elevational view of the needle threading device embodying this invention and showing the needle carrying arm moved out of transverse alinement with the thread carrying arms,

Figure 2 is a similar view to Fig. 1 and shows the needle in position on the needle carrying arm and the thread in position on the pair of thread carrying arms,

Figure 3 is a side elevational view of the threading device with one of the thread carrying arms broken away for showing the relative position of the needle carrying arm in respect to the thread carrying arms when the former is moved into a position in readiness for having the needle removed therefrom for threading the same,

Figure 4 is a top plan view of the threading device with the needle and thread in position upon their respective arms and with all of the elements in position for permitting the needle to be removed from its supporting arm for threading the same,

Figure 5 is a fragmentary end elevational view with one of the thread carrying arms broken away and with the needle removed from its supporting arm for indicating the position of the thread and the element which draws the same through the needle eye,

Figure 6 is an elevational view of the needle with the thread looped and being drawn through the eye, and

Figure 7 is an elevational view of the needle with the thread completely drawn through the eye so that only one strand of the same extends through said eye.

In the drawing, wherein for the purpose of illustration is shown a preferred embodiment of this invention, the numeral 5 designates the pair of thread carrying arms which are of substantially rectangular formation at their inner or finger grasping ends 6 and taper forwardly to their operating ends 7. The operating ends 7 of these thread carrying arms 5 are each provided with an upstanding lug 8 which is formed at substantially right angles to the longitudinal axis of the said arm. By inspecting Fig. 4, it will be seen that one of these arms is provided at its inner or finger grasping end 6 with a laterally extending flange 9 which is adapted to overlap the upper edge of the second thread carrying arm 5 when the same are in transverse alinement. This laterally extending flange 9 is provided with a depending ear 10 which is adapted to engage the outer side face of the second thread carrying arm 5 when the said arms are in the position shown in Figs. 1 to 4 inclusive or with the said arms in transverse alinement.

Pivottally connected to the thread carrying arms 5, as at 11, is a needle carrying arm 12 which is of substantially rectangular formation at its inner end 13 and has its lower edge beveled, as at 14, for providing a narrow or sharpened operating end 15 which is provided with a downwardly curved portion 16. The inner end 13 of this needle carrying arm is provided with a laterally extending flange 17 which is adapted to engage the lower edge of the thread carrying arm 5 which is provided with the flange 9, when all of the arms are moved into transverse alinement, as shown in Figs. 3 to 5 inclusive.

It will be seen by inspecting Figs. 1 to 4 inclusive, that the thread carrying arms 5 and needle carrying arm 12 are of substantially equal length and that the downwardly curved end portion 16 of the needle carrying arm will be sandwiched between the upstanding lugs 8 carried by the thread carrying arms 5 when all of the said arms

are moved into transverse alinement. By inspecting Fig. 4, it will be seen that the operating ends 7 of the thread carrying arms 5 are slightly bent outwardly or away from each other for providing suitable spaces between the adjacent faces of the three arms 5 and 12.

The operation of the threading device is as follows:—

- 10 The needle carrying arm is first positioned, as shown in Fig. 1, to form an X with respect to the thread carrying arms 5. The needle N is then positioned upon the operating end 15 of the needle carrying arm with the downwardly curved portion 16 inserted through the eye of the needle. With the needle and its carrying arm 12 still in their said positions, the thread T is laid over the operating ends 7 of the thread carrying arms 5 and allowed to depend downwardly from the outer sides of the same, as illustrated in Fig. 2. The needle carrying arm 12 is then pivoted to bring the same into transverse alinement with the thread carrying arms 5, as indicated in Fig. 3. It will then be seen that the thread T is clamped between the spaced ends 7 of the arms 5 and the downwardly curved end 16 of the needle carrying arm 12. With the various elements in these positions, the needle is then moved off of the curved end 16 of the arm 12 and this downwardly curved end 16 will draw the thread T through the eye of the needle N, in loop formation, as illustrated in Fig. 5. The thread may then be removed from the hooked end 16 and the needle N and thread T will have the appearance as shown in Fig. 6. The short end of the thread may then be withdrawn from the needle eye and the needle and thread will be in readiness for use, as illustrated in Fig. 7. It is to be understood that the oppositely directed flanges 9 and 17

carried by the thread carrying arm and needle carrying arm 5 and 12, operate to 45 properly transversely aline the various arms when they are moved into the positions shown in Figs. 3 and 4. The depending ear 10 formed in the laterally extending flange 9 engages the outer face of the opposite 50 thread carrying arm 5 for the purpose of frictionally engaging the same to retain the arms 5 in their transverse alinement.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. In a needle threading device, a series of arms pivotally connected together intermediate their ends, two of said arms having upstanding lugs carried by their adjacent ends and the third arm having a downwardly directed curved end adapted to be moved into transverse alinement with the 70 said upstanding lugs.

2. In a needle threading device, a pair of pivotally connected arms having upstanding lugs at their adjacent ends adapted for supporting a piece of thread placed inwardly of 75 said upstanding lugs and an arm pivotally positioned between the pair of arms having a downwardly curved end that is adapted to be inserted through the eye of a needle and moved into transverse alinement with 80 the upstanding lugs so that when the needle is withdrawn from its supporting arm the thread will be drawn through the eye of the same.

In testimony whereof I affix my signature.
HERMAN TRZECIAK.
